ADJUSTABLE FASTENER

Leo Roseman, Newark, N. J.

Application July 3, 1946, Serial No. 681,255

2 Claims. (Cl. 24—206)

1

This invention relates in general to fasteners of the type which includes a plurality of fastener elements such as bars, hooks, eyes, eyelets and the like that are attached to one of two parts to be fastened together to cooperate selectively with a hook or the like that is connected to the other of said parts, whereby said parts, which may be, for example, two portions of a garment or an article, can be adjustably fastened together.

One object of the invention is to provide a fastener of this general character which shall include novel and improved fastener elements, preferably rigid elements formed of wire, secured to a piece of tape or a garment in a novel and improved way, whereby the fasteners shall be thin, flat, flexible, devoid of projections that may cause discomfort to the wearer of a garment embodying the fastener, and at the same time shall be strong and durable.

Another object is to provide a combination of a flexible body section, such as a piece of fabric tape, and a novel and improved fastener element secured to the tape by stitches, whereby the fastener element may be easily located by the sense of touch, and the fastener element shall cooperate with the stitches in a novel and improved way so that the fastener element shall be firmly held against movement in all directions in its own plane and some of the strain imposed upon the fastener element by the hook section of the fastener shall be distributed through the stitches in such a way as to reduce the tendency of such strains to tear the fastener elements off the body section or tape.

A further object is to provide a novel and improved fastener element for fasteners of this character, which shall comprise a piece of wire or the like so shaped as to effectually interlock with stitches for applying the fastener element to a body section or tape, reduce the possibility of the fastener element cutting the stitches or the tape and prevent longitudinal movement of the element.

Other objects are to provide a novel fastener element of the character described which shall have a novel shape whereby the stitches utilized for fastening it to the tape or body section shall be disposed below the general plane of the side of the tape that might contact with the body of the wearer, whereby to prevent irritation to the skin of the wearer by such stitches; to provide such a fastener element so shaped that a plurality thereof may be easily and quickly slipped over or stacked on a magazine strip for use with sewing machines that may be employed for attaching

2

the fastener elements to the tape, and to obtain other advantages and results as will be brought out by the following description in combination with the accompanying drawing in which

5 Figure 1 is a fragmentary top plane view of an adjustable fastener embodying my invention, portions being broken away for clearness of illustration.

10 Figure 2 is a vertical longitudinal sectional view, on an enlarged scale, taken on the plane of line 2—2 of Figure 1.

Figure 3 is an enlarged transverse vertical sectional view on the plane of the line 3—3 of Figure 1.

15 Figure 4 is a fragmentary top plan view of a modified form of the invention, with portions broken away.

Figure 5 is an enlarged transverse vertical sectional view on the line 5—5 of Figure 4.

20 Figure 6 is a view similar to Figure 4 showing another modification of the invention.

Figure 7 is a like view showing a further modification of the fastener.

25 Figure 8 is a view similar to Figure 4 showing a modification of the invention to include the hook fastener element.

Figure 9 is an enlarged vertical longitudinal sectional view on the line 9—9 of Figure 8.

30 Figure 10 is a fragmentary top plan view of a further modification of the invention including another type of hook fastener element.

Figure 11 is an enlarged vertical longitudinal sectional view on the line 11—11 of Figure 10.

35 Figure 12 is a perspective view showing a double fastener embodying the invention, and

Figure 13 is a fragmentary schematic perspective view showing the manner of stacking the fastener elements on a fastener holding strip for a magazine.

40 Specifically describing the embodiment of the invention illustrated in Figures 1, 2 and 3, inclusive, the reference characters A and B designate the two sections of my fastener, one of which includes a plurality of fastener elements C which selectively cooperate with the other section B of the fastener which is in the form of a hook.

45 While the invention contemplates the application of the fastener elements C and the hook B directly to two parts to be connected for example, to portions of a garment or article, the invention more particularly contemplates a fastener wherein the fastener elements are connected to a tape or strip which may be applied to a portion

of a garment or article generally designated D, and the hook B is connected to a tape or the like which may be connected to the other portion of the garment or article.

More specifically describing the invention, the part A comprises a body strip 1 of suitable material, for example, flexible fabric that preferably has its edge portions folded inwardly as at 2 upon the same side of the strip, and the fastener elements C are secured between the main portion of the strip and said infolded edge portions with their intermediate portions exposed in a channel which is formed between the margins 3 of the infolded edge portions 2. Preferably a cushioning strip 1a, e. g. flannel, is interposed between the fastener elements and the main portion of the strip 1.

Each fastener element comprises a length of round wire 4 the intermediate portion 5 of which is substantially straight while its end portions are curved inwardly toward each other in spaced relation to the straight portion 5 to form inwardly opening loops 6, the extremities of the wire extending from the ends of the respective loops approximately perpendicularly to the straight intermediate portion 5 as indicated at 7.

The fastener elements are disposed on the top section, base or tape 1 with their loops 6 located between the main portion of the strip and the respective inturned edges 2, and the fastener elements are secured to the base, strip or tape by continuous lines of stitches 8 which can be formed in one continuous operation, each of which extends longitudinally along the margin of each inturned edge portion 2, certain of said stitches traversing the straight portions 5 of the fastener elements inwardly of the loops 6 as indicated at 9, there being preferably a plurality of the stitches 8 superimposed upon each other to provide a firm attachment of the fastener elements to the strip 1. As shown, these stitches 8 and 9 pass through all of the layers or plies of the strip including the main portion and the inturned edge portions, and also run closely adjacent to the inner sides of the straight end portions 7 of the fastener elements.

With this construction, the terminal portions 7 of the fastener elements abut the stitches 8 so as to prevent their movement longitudinally of themselves and transversely of the strip 1 and also to transfer thereto and distribute over the strip some of the strains imposed on the fastener elements by the hook; and these terminal portions also restrain any tendency of the fastener elements to rotate. Furthermore, these terminal portions reinforce the edge portions 3 of the strip 1 that form the walls of the channel for the hook B, while the curved loops 6 permit the stitches 9 to be located closely adjacent the margins 3 of the strip and close to the zone of strain imposed upon the straight portions 5 of the fastener elements by the hook B. The curved loops 6 and the terminal portions 7 reduce the possibility of the fastener elements cutting through the stitches or the fabric of the strip.

Another advantage of the fastener element shaped as above described, is that it may be easily slipped over and held upon a fastener holding strip or bar E (Figure 13) that is commonly used in magazines for fastener elements in sewing machines which are employed for stitching fastener elements to tapes, garments or articles.

A modification of the invention is shown in Figure 4 where the fastener element F is in gen-

eral similar to the element C but does not have the straight terminal portions 7. The element F is simply a straight piece of round wire having its end portions bent inwardly to form the open loops 10 corresponding to the loops 6.

It may be desirable in some instances to make the intermediate portions of the fastener elements curved as indicated at 11 in Figure 5 and to cause the lines of stitches 12, corresponding to the stitches 8, to traverse the said curved portions of the fastener elements and thereby draw the underside 13 of the base or body strip 14 upwardly against the curved portion 11, so that the ends of the stitches at the underside of the body strip are located above the general plane of the underside of said strip in such a manner as to reduce the possibility of irritation by said stitches to the skin of the wearer of a garment to which the fastener is attached.

Another modification is shown in Figure 6 of the drawing where the fastener element G comprises a straight piece of round wire having its end portions 15 bent at right angles to the intermediate portion 16.

Figure 7 shows still another form of the invention where the fastener element H consists of merely a straight piece of round wire 17.

The fastener elements F, G and H are secured to the respective bases, body strips or tapes 14, 18 and 19 in substantially the same manner that the fastener elements C are fastened to the tape or base 1.

It may be desirable in some instances to make a double fastener tape, in which case two pieces J and K of the tape like those shown in Figures 1, 4, 6 or 7 may have their corresponding ends secured together in any suitable manner, e. g. by binding tape 21, or by zigzag stitching, overlocking stitching, marrowing, etc. The other ends of the strips may be secured to a garment or other article L in any suitable manner, as shown in Figure 12.

The invention also contemplates fastener elements of the hook type as well as fastener elements of the eye type and Figures 8 to 11, inclusive, show modifications of the invention wherein hook and fastener elements are embodied.

Referring particularly to Figures 8 and 9, the structure is essentially the same as that illustrated in Figures 1 and 2 except that instead of the straight rigid bar portion 5, the intermediate portion of the fastener element is in form of a hook bill 22. The base of the hook includes the loop. Portions 23 and straight terminal portions 24 corresponding to the loops 6 and terminal portions 7 and the superposed stitches 25, which correspond to the stitches 9, traverse the base portion of the hook close to the bill 22 and along the margins of the inturned portions 26 of the body strip 27 of the fastener part.

In Figures 10 and 11, a known type of wire hook is included which comprises an approximately rectangular base portion 28 centrally from one side of which projects a bill 29. The superposed stitches 30 corresponding to the stitches 9 traverse the said side of the base portion 28 of the hook closely adjacent the hook bill and along the margins of the inturned edge portions 31 of the base strip 32.

It will be noted that in all forms of the invention, the superposed stitches pass through all of the plies of the main portions and the inturned edge portions of the base strips, instead of only through a carrier strip such as is common in the prior art, for example Patent No. 2,282,410.

With this construction, all of the fastener elements can be applied to the base strip in one continuous sewing operation, and the fastener is strong and durable.

It will also be noted that where the fastener element is a hook, the hump and bill of the hook are fully exposed and not covered by cloth, whereby attachment of the hook to a complementary eye shall not be hindered by layers of cloth between the bill and the base of the hook. This construction also eliminates the difficulty encountered in known hook fasteners which arises from wear of the fabric that overlies the hump of the hook. However, the major portion of the base of the hook is covered and concealed by the fabric of the tape.

While I have shown in each case a base strip having two or more fastener elements on it, it will be understood that the invention contemplates fasteners wherein there is only one hook or eye on the base strip.

Other modifications in the construction and use of the tape will occur to those skilled in the art within the spirit and scope of the invention.

What I claim is:

1. An adjustable fastener part comprising a base strip having longitudinal edges folded at the same side of the strip with their margins forming a channel between them, a plurality of fastener elements spaced longitudinally of said strip, each including a main rigid bar portion extending transversely of said channel having end portions each returned parallel and in opposed spaced relation to and at the same side of said rigid bar portion to form an inwardly facing open loop, said end portions being located between said infolded edge portions and the main portion of said strip, and a continuous single line of stitches running longitudinally along the margin of each in-turned edge portion inwardly of and closely adjacent said returned end portions of said fastener elements and penetrating said edge portions and said main portion of said base strip, certain of said stitches in each line traversing said rigid bar portions.

45

2. An adjustable fastener part comprising a base strip having longitudinal edges folded at the same side of the strip with their margins forming a channel between them, a plurality of fastener elements spaced longitudinally of said strip, each including a main rigid bar portion extending transversely of said channel having end portions each returned parallel and in opposed spaced relation to and at the same side of said rigid bar portion to form an inwardly facing open loop and then extending perpendicularly to said bar portion to form terminal portions, said end portions being located between said infolded edge portions and the main portion of said strip with said terminal portions disposed adjacent the respective margins of said infolded edge portions, and a continuous single line of stitches running longitudinally along the margin of each in-turned edge portion inwardly of and closely adjacent said terminal portions and penetrating said edge portions and said main portion of said base strip, certain of said stitches in each line being disposed in abutting relation to each of said rigid bar portions.
